[57] **CLAIM**

The ornamental design of a holster for drill and/or screwdriver bits, as shown and described.

DESCRIPTION

FIG. 1 is a perspective view of my design of a holster for drill and/or screwdriver bits affixed to a motorized drill which is represented by broken lines. The broken lines shown in FIG. 1 are for illustrative purposes only, and form no part of the claimed design; FIG. 2 is a perspective view of the holster shown in FIG. 1 as seen from the top and right side; FIG. 3 is a top plan view of the holster shown in FIG. 2; FIG. 4 is a left side elevational view of the holster shown in FIG. 2; FIG. 5 is a front elevational view of the holster shown in FIG. 2; FIG. 6 is a right side elevational view of the holster shown in FIG. 2; FIG. 7 is a rear elevational view of the holster shown in FIG. 2; and, FIG. 8 is a bottom plan view of the holster shown in FIG. 2.
